UNITED STATES PATENT OFFICE

118,775

DESIGN FOR AN ELECTRIC HEATER

Kemper M. Hammell, Toledo, Ohio, and Carl W. Sundberg, Detroit, Mich., assignors to The Swartzbaugh Manufacturing Company, Toledo, Ohio, a corporation of Ohio

Application December 5, 1939, Serial No. 88,687

Term of patent 7 years

To all whom it may concern:

Be it known that we, Kemper M. Hammell, of Toledo, Lucas County, Ohio, and Carl W. Sundberg, of Detroit, Wayne County, Michigan, both citizens of the United States, have invented a new, original, and ornamental Design for an Electric Heater, of which the following is a specification, reference being had to the accompanying drawing, forming a part thereof.

Fig. 1 is a perspective view of an electric heater showing our new design; Fig. 2 is a horizontal

cross-section on the line 2—2 in Fig. 1, and Fig. 3 is a fragmentary vertical cross-section on the line 3—3 in Fig. 1.

The dominant features of our design reside in the portions shown in full lines.

We claim:

The ornamental design for an electric heater, substantially as shown and described.

KEMPER M. HAMMELL.
CARL W. SUNDBERG.
